UNITED STATES PATENT OFFICE.

JAMES A. CROSBY, OF CHICAGO, ILLINOIS, ASSIGNOR TO SELIG POLYSCOPE COMPANY, OF CHICAGO, ILLINOIS, A CORPORATION OF ILLINOIS.

MOVING-PICTURE MACHINE.

No. 925,159.

Specification of Letters Patent.

Patented June 15, 1909.

Application filed January 25, 1909. Serial No. 474,044.

To all whom it may concern:

Be it known that I, JAMES A. CROSBY, a citizen of the United States, residing at Chicago, in the county of Cook and State of Illinois, have invented certain new and useful Improvements in Moving-Picture Machines, of which the following is a specification.

The present invention relates more particularly to the feeding mechanism of a moving picture machine; and the object of the invention is to provide means for securing an intermittent rotation for the feeding drum of the moving picture film. In mechanism of this kind it is customary to feed forward the film in unison with the rotation of the shutter, and in the present invention an intermittent rotation is applied to a pair of spur feeding wheels, the teeth of which are adapted to engage with the holes in the margins of the film, which method of feeding serves to carry forward the films smoothly and uniformly and without objectionable vibration, regardless of the speed of travel of the film.

A further object of the invention is to provide a lock for holding the feeding wheels rigid during the interval between each forward movement, thereby securing a positive forward movement of predetermined length and a sharp arrest of the film thereafter.

Further objects will appear from a detailed description of the invention, which consists in the features of construction and combination of parts hereinafter described and claimed.

In the drawings, Figure 1 is a side elevation of so much of a moving picture machine as pertains to the present invention, showing one of the supporting posts broken away; Figs. 2, 3, 4, and 5, side elevations of the operating cam and lock in different positions of movement, said views being taken from the reverse side of the machine to that shown in Fig. 1; and Fig. 6 a sectional plan view through the operating mechanism.

The moving picture machine, as regards its principal structural features, is of an ordinary type, comprising a floor plate 7, a roof plate 8, a front plate 9, and a rear plate 10. The roof and floor plates are connected, at the corners, by four posts 11, although, obviously, the framework of the machine might be otherwise constructed. Behind the rear plate is a guide frame 12 which is hinged, at its lower end 13, which guide frame is of an old and well known type and

serves to position the film during its travel through the machine. The present invention is not concerned with these features of construction, and further description is deemed unnecessary.

To the rear plate 10 is secured a journal sleeve 14, which provides a mounting for a substantially vertical transmission shaft 15, having at its lower end a bevel pinion 16 meshing with a driving pinion 17, which latter pinion is mounted upon a power shaft 18 journaled within a bracket 19. The power shaft has also mounted thereon a driving spur gear wheel 20, which meshes with a spur pinion 21 upon a cam shaft 22, which shaft also carries a fly wheel 23 to regulate and equalize the movements of the machine. The machine is driven by a handle 24 on the power shaft, or in any other suitable way. The vertical shaft 15 is provided, at its upper end, with a driving bevel pinion 25 which meshes with a driven bevel pinion 26 upon a feed shaft 27, suitably journaled at the upper end of the sleeve 14; and the feed shaft is provided, in alinement with the hinged guide plate 12, with toothed upper feed rolls 28, which are adapted to feed down the film from a suitable drum or reel, not shown, the film being held in engagement with the feed rolls by means of a compression roller 29 located to the rear of the feed wheel. The invention is not concerned in these features of the machine, and other feeding mechanism might be employed.

The invention more particularly relates to the lower or power driven feed wheels 30, which, as shown in Fig. 6, are two in number and are arranged to project through slots 31 in the rear plate 10, and are provided, at recurrent intervals around their peripheries, with teeth 32, which are suitably spaced to engage with the holes in the margins of a strip of film. The feed wheels are integrally formed on a hub 33, which is rigidly mounted upon a shaft 34 journaled within inner and outer journal blocks 35 and 36, which are screwed or otherwise rigidly secured to the inner face of the rear plate of the machine in position to bring the peripheries of the feed wheels into register with the hinged guide plate 12, which positions the film during its travels through the machine. The shaft 34 is provided, on its inner end, with a disk 37 having at determined intervals, inwardly projecting cylindrical studs

38, which, in the present instance, are six in number. The teeth in the feed wheels are so spaced that the film will be drawn forward the proper distance by the 5 engagement of a predetermined number of teeth with holes in the margins of the film, and in the present instance four teeth of the feed wheels will engage with the film during each forward movement thereof. The studs 10 on the disk coöperate with a feed plate 39, provided, in its inner end, with a slot or recess 40 of a suitable size to readily engage successively with the studs on the disk. The feed plate is secured to the forward rail 15 of a square open vertically reciprocable frame 41, which frame is slidably mounted within a rectangular horizontal reciprocating guide frame 42, which latter is held and guided within guide plates 45 and 46, respectively, which plates are screwed or otherwise rigidly secured in parallel relation to one another on the face of a supporting plate 47, the rear edge of which is rigidly secured to the inner face of the rear plate 10 25 of the machine, as best shown in Fig. 6. The inner vertical reciprocating frame surrounds a cam disk 48, which is of substantially triangular formation, the edges being slightly rounded out to better facilitate the 30 engagement thereof with the inner edges of the surrounding frame. The cam is rigidly secured to the end of the shaft 22, said shaft engaging the cam near one of the corners thereof, so as to provide for a very considerable cam action as the shaft is revolved. The longitudinally reciprocating frame has rearwardly extending from its rear rail a tongue 49 which operates through a slot 50 in the rear plate of the machine, which tongue 40 lies behind the studs of the disk 37, as shown in Fig. 6. The tongue is provided, near its end, on its forward face, with a locking block 51, which lies closely adjacent to the face of the disk 37 and is adapted, at 45 proper intervals in the reciprocation of the frame, to be drawn in between adjacent studs on the disk, so as to lock the disk at such intervals against either a forward or return movement. These are the intervals 50 at which the feed wheels are intended to be at rest, so that at these periods of time the film will be positively locked and held, regardless of the rapidity of its feeding movement. The locking block occupies a position 55 near the end of the tongue 49, and will be thrown to locking position with each forward movement of the frame with which the tongue is connected, whereas the feeding of the disk will take place with each rearward 60 movement of the frame, the feeding and locking movements being exactly timed to secure a perfect operation of the machine. The reciprocating frames are inclosed and 65 protected by means of a forward housing 52, and the locking members are inclosed and

protected by means of a rearward housing 53, which housings are preferably intended to be sufficiently tight to permit the mechanism above described to run in a bath of oil, if so desired. The cam shaft 22 has 70 mounted thereon a bevel pinion 54, which engages with a bevel pinion 55 on the inner end of a shutter shaft 56, which carries a shutter 57 of any suitable and well known style. 75

The operation of the machine is as follows: The end of the film will be drawn down into position to engage with the teeth of the upper feed rolls and lower feed wheels, being guided and positioned in the machine in the usual 80 manner. Thereafter, when the driving shaft is actuated, the driving spur gear wheel 20, which meshes with the spur pinion 21, will impart rotation to the cam shaft 22, which will rotate the triangular cam 48 to various 85 positions, as shown in Figs. 2, 3, 4, and 5. Beginning with the parts in the position shown in Fig. 2, in which both of the reciprocating frames are thrown forward, and the vertical reciprocating inner frame is lowered, 90 and in which the locking block occupies a position intermediate two of the studs, the first movement of the cam will draw back both the inner and outer frames into the position shown in Fig. 3, which throws the locking 95 block out of the path of travel of the studs, and throws the slotted feeding plate into engagement with one of the studs. The continued movement of the cam serves to elevate the inner reciprocating frame, without 100 changing the position of the outer reciprocating frame, and this movement serves to lift the feed plate and with it the previously engaged stud, in the position shown in Fig. 4, thereby imparting a partial revolution to the 105 disk 37, which partial revolution is imparted to the feed wheels, the teeth of which thereby serving to draw down the film sufficiently to permit an exposure or an exhibition to be made. The continued movement of the 110 cam, therefore, throws the parts into the position shown in Fig. 4, in which the outer reciprocating frame is thrown to its forward or locking position, and the inner frame to its elevated position, after which the inner 115 frame moves back to the forward position in preparation for a succeeding feeding movement of the character previously described.

The upper feed rolls, which are positively and constantly driven by the gearing previously described, are of lesser diameter than the lower feeding wheels which are intermittently driven, so that the increased diameter of the lower wheels will compensate for the interrupted feeding movement, so 125 that the film will be fed forward with sufficient uniformity by the two sets of feeding devices. In view of the fact that the film will not be stretched tight between the upper and lower feeding devices, it will not be nec- 130

essary to provide intermittent mechanism for the upper feed rolls, sufficient slack being afforded in the film to prevent the tearing thereof.

5 The mechanism of the present invention is intended to be applied either to a taking or to an exhibiting machine, and serves to afford a very perfect feeding tension on the film, which will be fed a predetermined distance each time without variation and without any vibration, which might tend to impair the resultant picture. A positive lock is afforded between each movement of the feeding rolls, in view of the fact that the 10 locking block in each case will move into engagement between an adjacent pair of studs before the slotted bar has moved back out of engagement with another of the studs, so that there will be absolutely no possibility 15 of any accidental movement of the feed wheels in the intervals between their feeding movements, regardless of the rate of speed at which the machine is operated. The movement, moreover, is easy and positive 20 and without any jerking, which might tend to stretch or strain the film, and the compact arrangement of the mechanism permits the parts to be inclosed in a bath of oil, which serves to render the operation of the machine 25 practically noiseless.

What I regard as new and desire to secure by Letters Patent is:

1. In a moving picture machine, the combination of a feed wheel, a disk connected 35 with the feed wheel and provided with projections, a member adapted to successively engage said projections, an inner reciprocating frame with which said member is connected, an outer reciprocating frame carrying 40 the inner reciprocating frame, and means for actuating said frames to impart to the engaging member the movements required to impart an intermittent feed to the disk, substantially as described.

45 2. In a moving picture machine, the combination of a feed wheel, a disk connected with the feed wheel and provided with projections, a member adapted to successively engage said projections, an inner reciprocating frame with which said member is connected, an outer reciprocating frame carrying 50 the inner reciprocating frame, means for actuating said frames to impart to the engaging member the movements required to impart an intermittent feed to the disk, and a

locking device on the outer frame adapted to be moved to a position intermediate the adjacent projections on the disk during the intervals of rest thereof, substantially as described.

3. In a moving picture machine, the combination of a feed wheel, a disk connected therewith and provided, on its face, with projections, a slotted feed plate adapted to cooperate with the projections on the disks, an 60 inner frame carrying the feed plate, an outer frame within which the inner frame is slidably mounted, a guideway for slidably mounting the outer frame to move in a direction transverse to the line of movement 65 of the inner frame within the outer frame, and a cam located within the inner frame and adapted to impart thereto movements required to bring the slotted feed plate, first into engagement with a projection, second to 70 move the feed plate in a direction to impart partial revolution to the projection, and lastly to withdraw the feed plate and return the same to initial position, substantially as described.

4. In a moving picture machine, the combination of a feed wheel, a disk connected therewith and provided, on its face, with projections, a slotted feed plate adapted to cooperate with the projections on the disk, an 80 inner frame carrying the feed plate, an outer frame within which the inner frame is slidably mounted, a guideway for slidably mounting the outer frame to move in a direction transverse to the line of movement of 85 the inner frame within the outer frame, a cam located within the inner frame and adapted to impart thereto movements required to bring the slotted feed plate, first into engagement with a projection, second to 90 move the feed plate in a direction to impart partial revolution to the projection, and lastly to withdraw the feed plate and return the same to initial position, a tongue on the outer frame, and a locking block on the 100 tongue adapted to be drawn into locking position between adjacent projections simultaneously with the withdrawing of the feed plate from a position of engagement, substantially as described.
